DISPENSING SLIDE MECHANISM

John C. Wahl, Chicago, Ill., assignor to Mills Novelty Company, Chicago, Ill., a corporation of Illinois

Application May 26, 1934, Serial No. 727,677

12 Claims. (Cl. 312—48)

This invention relates to dispensing devices for metal checks or the like used for operating check-controlled amusement machines, or for other purposes, and has for its general object the provision of a device of this character which is simple and efficient in construction and operation, and which is more certain in its action and less likely to get out of order than devices for this purpose which have heretofore been in use.

10 A more particular object of the invention is the provision in such a device of means to prevent jamming or breakage of parts of the mechanism in case checks of inexact dimensions, as those which are too thick or too thin, find their way into the device and cause misalignment with the operating mechanism.

Another important object is the provision of a device of this character in which the checks are arranged in a stack and those to be discharged on any particular operation of the device are merely separated from the lower part of the stack by one of a series of separating slides operating in conjunction with a supporting and release slide normally positioned underneath the stack and adapted to be moved out of supporting position simultaneously with the advance of any one of said separating slides.

Other objects of the invention will be apparent as I proceed with my specification, which, taken in connection with the accompanying drawings, discloses a preferred embodiment thereof.

Referring to the drawings:

Fig. 1 is a top plan view of a device in which my invention is embodied;

Fig. 2 is a partial longitudinal section taken along the line 2—2 in Fig. 1;

Fig. 3 is a plan view of the device with the top plate removed and showing certain of the parts in different positions from those shown in Fig. 1;

Fig. 4 is an end elevation taken from the right in Figs. 1 and 3;

Fig. 5 is a side view of the device looking in the direction of the arrows indicated at 5—5 in Fig. 1; and

Fig. 6 is a side elevation looking in the direction of the arrows indicated at 6—6 in Fig. 1.

The device shown in said drawings, as an illustrative embodiment of the invention, comprises a base plate 11 having an aperture 12 near one end thereof and having mounted thereon a release slide or gate 13 and a plurality of slides 14, arranged in stacked relationship with spacing members therebetween, including plates 15 and yielding members 56, which will be more fully described hereinafter, said base plate 11 also sup-

porting the operating mechanism for said slides, which mechanism will be hereinafter specifically described. It will be understood that the device is adapted to be positioned in a vending or amusement machine, and will be suitably supported in proper relationship to certain mechanism of the machine adapted to control the operation of the device and also in suitable position for the discharge of tokens or other contents of the device into a discharge chute leading to a tray, from which they may be removed by the operator of the machine. The separating slides are formed with apertures which are normally in alignment with openings formed between the spacing plates 15 and yielding members 56, to provide a vertical chute 16 adapted to contain a column of metal tokens or checks which may be delivered thereto through a tube 17 fragmentarily shown in the drawings. The gate 13 has an aperture 18 which is normally out of registration with the chute 16, as shown in Fig. 2 of the drawings, but is adapted to be moved into registration with said chute when said gate is advanced to the forward position shown in Fig. 3.

The spacing plates 15 are held in fixed position by means of screws 19 at the four corners of the assembly, as shown in Fig. 1, and the separating slides 14 are mounted for sliding action between said plates being held in place by means of a screw 21 extending through elongated slots 22 in the slides. Said slides are pivotally connected at their rear ends with actuating links 23 which are slotted at 24 to receive lugs 25 on bell crank levers 26 which are pivoted at 27 and are normally held in the position shown in Fig. 1 by means of springs 28 connected at one end to hooks 29 on said levers 26, and at the opposite end to fixed hooks 31 protruding from the spacing plates 15. The lateral arms 32 of said bell crank levers 26 are formed with lugs 33 on one side thereof, and the ends 34 of said arms extend through slots 35 in an upstanding plate 36 at the outer extremity of a laterally projecting portion 37 of the base plate 11.

On the rear end of the gate 13 there is provided an actuating member 38 pivoted on a stud 39, and having at its outer end an angular flange 41 adapted to engage a shoulder 42 at the forward end of a recess 43 formed in the side of the links 23 connecting the bell crank levers 26 with the separating slides 14. A spring 44 extends between a hook (not shown) on the member 38 and a hook 46 formed on one of the fixed spacing plates 15. Said spring thus serves to draw said gate 13 forwardly when the latter is released.

for such movement as will presently appear. A pin 38a mounted in the gate 13, limits the forward movement of the member 38 under the pull of the spring 44.

5 Said gate 13 also has a stud 47 on the upper face thereof which is adapted to be engaged by an actuating mechanism (not shown) to move said gate to the position shown in full lines in Fig. 1, in which position it is normally held. Upon release of said stud 47, which may be accomplished by disengaging the actuating mechanism therefrom in any suitable manner, said gate 13 will be permitted to move forwardly under the influence of the spring 44, and the parts will be 10 moved to the position shown in dotted lines in said Fig. 1, being stopped in this position (in case the members 26 and 23 are not actuated) by the engagement of a dog 48, formed on the lower part of the pivoted member 38, with an upstanding 15 lug 49 at the edge of the base plate 11. If, however, one of the bell crank levers 26 has been moved in clockwise direction on the pivot 27, thereby moving the corresponding link 23 in clockwise direction on its pivot, the flange 41 20 will engage the shoulder 42 on said link 23, causing the latter to be moved and the separating slide 14 to which it is connected forwardly to the 25 position shown in Fig. 3. It will be noted from the latter figure that the engagement of said flange 41 with said shoulder 42 causes the member 38 to turn in clockwise direction on its pivot 30 39 when the slide 13 is moved forwardly, and this turning action causes the dog 48 to clear the stop lug 49, thus permitting the release gate 13 35 and the separating slide 14 to move to their full forward position, as shown in said Fig. 3. This action will cause the portion of the separating slide at the rear of the aperture therein to move into the chute 16, advancing the check in alignment with such slide and supporting the checks 40 in the stack above the level of said slide. The retracted and advanced position of said slide are shown in Figs. 1 and 3, respectively, from which 45 it will appear that the slides constitute aper-tured plates, the forward ends of which are nor-mally in the position shown in Fig. 1 and are adapted to be advanced to the position shown in Fig. 3. Inasmuch as the forward movement of 50 the gate 13 at the same time brings the opening 18 therein into registration with the bottom of the chute 16, all checks below the particular separating slide which has been operated, will be allowed to drop out through the opening 12 in the base plate 11, and will fall into the delivery 55 tray (not shown) from which they may be removed by the operator. The forward end of the gate 13 is serrated, as indicated at 51, and at the end of the forward stroke of said gate engages a stop member 52 beneath a guard 53, which stop 60 member and guard are secured to the base plate 11 by means of screws 54.

In case the checks or other discs 55 in the chute 16 are not of uniform thickness, it may be that they would not be in alignment with the 65 slides 14 and spacing plates 15, and in this case there would be a tendency for the device to jam, with consequent danger of breakage or distortion of certain parts, except for an important feature of my invention which will now be described. I 70 provide pivoted members 56 above and below each of the slides 14, said members being pivoted on a pivot pin 57 extending upwardly from the base plate 11, said members being normally held in the position shown in Fig. 1 of the drawings by 75 means of springs 58 connected at one end with

hooks 59 on said members 56 and at the other end with hooks 61 on fixed spacing plates 62, which are in alignment with the plates 15 and are held in place by means of the forward screws 19. The forward ends of said members 56 5 are of arcuate form, as shown in Figs. 1 and 3, and are adapted to yield against the tension of the springs 58 when one of the checks or discs is forced thereagainst by the actuated separating slide 14. This will permit completion of the cycle of operation of the device, and, when said slide has returned, the member 56 will be returned to its normal position by the action of the spring 58. This is a highly desirable feature since it is not infrequent that one or more of the discs 15 in the chute are too thin or are otherwise of abnormal dimension so that the problem solved by this improvement is a serious one from the stand-point of practical use of the device.

The selection of the slide to be operated (which 20 of course determines the number of checks or discs to be released upon any actuation of the device) is controlled by levers (not shown), which may extend through slots 63 in the lateral extension 37 of the base plate 11, said levers corresponding in number to the number of bell crank levers 26 and the lugs 33 on the arms 32 of said bell crank levers, being arranged to correspond to the number of operating levers, whereby the operation of one of said levers will operate the cor- 25 responding bell crank 26. The elbow portions of said bell cranks are positioned in slots 64 in a plate 65, and the outer ends 66 of the links 23 are disposed in slots 67 in a plate 68, both said plates extending upwardly from the base plate 11 to 30 which they are secured. The links 23 are provided with lugs 69, forming the rear wall of the recesses 43, said lugs being adapted to be engaged by the member 38 on the return stroke thereof to move the operated link and the separating 35 slide, to which it is connected, back to the normal position shown in Fig. 1 after the device has been operated.

The operation of the device may be briefly 45 summarized as follows:

Assuming that the chute 16 is filled with checks or other discs (as it normally will be since checks inserted in the machine will be continually directed through the tube 17 to said chute), the 50 actuation of the machine will move the control member which cooperates with the stud 47, such movement allowing the slide 13 to move forwardly under the influence of the spring 44, which, as above stated, is connected at one end 55 with the member 38 mounted on said slide. If none of the bell cranks 26 is operated, the gate or plate 13 will move only to the dotted line position shown in Fig. 1, in which position it will be stopped by engagement of the dog 48 60 with the lug 49. The reverse stroke of the mechanism will then move said slide back to the full line position shown in Fig. 1, and none of the 65 checks in the chute 16 will be released since the movement of the gate 13 will not have been sufficient to bring the aperture 18 therein into alignment with the aperture 12 in the base plate 11. However, if one of the bell cranks 26 has been actuated by action of one of the control levers against the lug 33 on the arm 32 of said 70 bell crank, the corresponding link 23 will have been moved in the initial stages of the operation from the position shown in Fig. 1 to that shown in Fig. 3, disposing the shoulder 42 on said link in the path of the flange 41 on the member 38, which will result in turning said member 38 on 75

its pivot to the position shown in Fig. 3 and advancing the link 23 and the slide 14 to which it is connected to the forward position shown in said figure. The stroke may be completed by 5 reason of the fact that the turning of the member 38 on its pivot will have moved the dog 48 on said member inwardly as shown, thus causing it to clear the lug 49, this action also permitting the gate 13 to advance to its full forward position, thereby bringing the aperture 18 into registration with the aperture 12 and allowing all 10 checks beneath the actuated separating slide to drop through said aligned apertures into a delivery chute and tray, as above described. In 15 case the checks, due to improper thickness or other cause, are out of alignment in the chute 16 so that the advancing slide will engage the check above or the one below the level of the slide, such check will engage one of the members 20 56, which will yield against the tension of its associated spring 58, thus allowing the stroke to be completed without damage to the device or the operating mechanism of the machine, as otherwise might occur. When the operating 25 parts have returned to normal position, said member 56 will be returned to the position shown in Fig. 1 by the action of the spring 58, thereby returning the check to its position in the chute. The machine may then be opened, and the check 30 or checks which have caused the misalignment removed.

It will be observed that in the operation of the device, it is not necessary to carry the checks forwardly to a point of delivery as in former 35 mechanisms, nor is it necessary to move more than one slide to release a plurality of checks, since all checks beneath the actuated separating slide will be released through the actuation of but one separating slide and the release gate 40 or plate 13, in the manner hereinabove described.

The foregoing detailed description has been given for clearness of understanding only, and no unnecessary limitations should be understood therefrom, but the appended claims should be 45 construed as broadly as permissible, in view of the prior art.

What I regard as new and desire to secure by Letters Patent is:

1. A dispensing device for metal checks or 50 the like comprising a plurality of slides and spacing members arranged alternately in stacked relationship said slides and spacing members being formed to provide, when in normal relationship to each other, a chute for receiving a stack of checks, a gate member mounted beneath said slides, and means for advancing a selected one of said slides to cause such slide to support the checks in the stack above such slide and for moving said gate member out of supporting relation to said stack, thereby releasing for discharge all checks beneath said slide.

2. A dispensing device for metal checks or the 55 like comprising a plurality of slides and spacing members arranged alternately in stacked relationship said slides and spacing members being formed to provide, when in normal relationship to each other, a chute for receiving a stack of checks, a gate mounted beneath said slides, means for advancing a selected one of said slides to cause such slide to support the checks in the stack above such slide and for moving said gate out of supporting relation to said stack, thereby releasing for discharge all checks beneath said slide, said spacing members including plates arranged between the slides on the rear side of

said chute and yielding members positioned between said slides on the forward side of said chute each in the same plane with its respective plate, said yielding members being adapted to yield under pressure of checks forced against the same by an advancing slide in case of misalignment of the checks in the chute. 5

3. A dispensing device for metal checks or the like comprising a plurality of slides and spacing members arranged alternately in stacked relationship said slides and spacing members being formed to provide, when in normal relationship to each other, a chute for receiving a stack of checks, a gate mounted beneath said slides, means for advancing a selected one of said slides to 10 cause such slide to support the checks in the stack above such slide and for moving said gate out of supporting relation to said stack, thereby releasing for discharge all checks beneath said slide, said spacing members including plates arranged between the slides on the rear side of said chute yielding members positioned between said slides on the forward side of said chute each in the same plane with its respective plate, said yielding members being adapted to yield under pressure of checks forced against the same by an advancing slide in case of misalignment of the checks in the chute, and spring means for returning said yielding members to normal position when the pressure is released. 15

4. A dispensing device for metal checks or the like comprising a plurality of slides and spacing members arranged alternately in stacked relationship said slides and spacing members being formed to provide, when in normal relationship 20 to each other, a chute for receiving a stack of checks, a gate mounted beneath said slides, means for advancing a selected one of said slides to cause such slide to support the checks in the stack above such slide and for moving said gate 25 out of supporting relation to said stack, thereby releasing for discharge all checks beneath said slide, said spacing members including plates arranged between the slides on the rear side of said chute and pivoted members of arcuate formation positioned between said slides on the forward side of said chute each in the same plane with its respective plate, said yielding members being adapted to yield under pressure of checks forced against the same by an advancing slide 30 in case of misalignment of the checks in the chute. 35

5. A dispensing device for metal checks or the like comprising a plurality of slides and spacing members arranged alternately in stacked relationship said slides and spacing members being formed to provide, when in normal relationship to each other, a chute for receiving a stack of checks, a gate mounted beneath said slides, links pivotally connected to said slides, control members 40 connected with said links and adapted, when one of said members is actuated, to move an associated link laterally, means for moving said gate out of supporting relation to said stack, and means movable with said gate for engaging a 45 protruding part of the laterally displaced link to move the same and the slide to which it is connected forwardly to cause said slide to support the checks above said slide. 50

6. A dispensing device for metal checks or the 55 like comprising a plurality of slides and spacing members arranged alternately in stacked relationship said slides and spacing members being formed to provide, when in normal relationship to each other, a chute for receiving a stack of 60

checks, a gate mounted beneath said slides, links pivotally connected to said slides, control members connected with said links and adapted, when one of said members is actuated, to move an associated link laterally, means for moving said gate out of supporting relation to said stack, a pivotally mounted device movable with said gate for engaging a protruding part of the laterally displaced link to move the same and the slide to which it is connected forwardly to cause said slide to support the checks above said slide, and stop means engageable by said last mentioned device, in case one of said links has not been displaced laterally to position to engage said device and turn the same on its pivot, said stop means in such event preventing movement of said supporting and release member out of supporting position.

7. A dispensing device for metal checks or the like comprising a plurality of slides and spacing members arranged alternately in stacked relationship said slides and spacing members being formed to provide, when in normal relationship to each other, a chute for receiving a stack of checks, a gate mounted beneath said slides, links pivotally connected to said slides, control members of bell crank formation connected with said links and adapted when one of said members is actuated to move an associated link laterally, means for moving said gate out of supporting relation to said stack, and means movable with said gate for engaging a protruding part of the laterally displaced link to move the same and the slide to which it is connected forwardly to cause said slide to support the checks above said slide.

8. A dispensing device for metal checks or the like, means forming a chute for receiving a stack of checks, said means including a plurality of movable slides having normally aligned apertures therein in which said stack of checks is received, a gate normally closing said opening and retaining the checks therein, means for advancing said gate and a selected one of said slides to move the gate out of its closing position and cause said slide to support the checks above the same in said chute, thereby allowing the checks beneath said slide to be discharged, and controllable means for effecting interconnection between said plate and one or another of said slides upon each operation of the device.

9. A dispensing device for metal checks or the like, means forming a chute for receiving a stack of checks, said means including a plurality of movable slides having normally aligned apertures therein in which said stack of checks is received, a gate normally closing said opening and retaining the checks therein, means for advancing said gate and a selected one of said slides to move the gate out of its closing position and cause said slide to support the checks above the same in said chute, thereby allowing the checks beneath said slide to be discharged, controllable means for effecting interconnection between said plate and one or another of said slides upon each operation of the device, and yielding members intermediate said slides positioned forwardly of said opening for preventing jamming of the device in

case, due to varying thickness of the checks, or to other cause, the operated slide should engage the check above or the one below the level of said slide, thus forcing the same against one of said yielding members.

10. A dispensing device for metal checks or the like, means forming a chute for receiving a stack of checks, said means including a plurality of movable slides having normally aligned apertures therein in which said stack of checks is received, a gate normally closing said opening and retaining the checks therein, means for advancing said gate and a selected one of said slides to move the gate out of its closing position and cause said slide to support the checks above the same in said chute, thereby allowing the checks beneath said slide to be discharged, controllable means for effecting interconnection between said plate and one or another of said slides upon each operation of the device, and pivotally mounted yielding members intermediate said slides positioned forwardly of said opening for preventing jamming of the device in case, due to varying thickness of the checks, or to other cause, the operated slide should engage the check above or the one below the level of said slide, thus forcing the same against one of said pivotally mounted yielding members.

11. A dispensing device for metal checks or the like, means forming a chute for receiving a stack of checks, and means including a plurality of movable slides having normally aligned apertures therein in which said stack of checks is received, a gate normally closing said opening and retaining the checks therein, means for advancing said gate and a selected one of said slides to move the gate out of its closing position and cause said slide to support the checks above the same in said chute, thereby allowing the checks beneath said slide to be discharged, controllable means for effecting interconnection between said plate and one or another of said slides upon each operation of the device, pivotally mounted yielding members intermediate said slides positioned forwardly of said opening for preventing jamming of the device in case, due to varying thickness of the checks, or to other cause, the operated slide should engage the check above or the one below the level of said slide, thus forcing the same against one of said pivotally mounted yielding members.

12. A dispensing device for metal checks or the like comprising a plurality of movable separating slides having normally aligned apertures therein, a slidable release plate mounted beneath said separating slides, and means for moving a selected one of said separating slides and said release plate to cause said slide to support the checks above the level of said slide in a stack thereof arranged in the opening provided by said aligned apertures, and to cause said release plate to move out of supporting relation to said stack of checks whereby all checks beneath said separating slide will be discharged from the device.

JOHN C. WAHL.
